UNITED STATES PATENT OFFICE.

WILLIAM N. NELSON, OF AMARILLO, TEXAS.

DESIGN FOR AN ASH TRAY.

Application filed May 17, 1929. Serial No. 31,268. Term of patent 3½ years.

To all whom it may concern:

Be it known that I, WILLIAM N. NELSON, a citizen of the United States, residing at Amarillo, in the county of Potter and State of Texas, have invented a new, original, and ornamental Design for an Ash Tray, of which the following is a specification, reference being had to the accompanying drawing, forming part thereof.

Figure 1 is a perspective view of an ash tray, and

Figure 2 is a similar view thereof taken at a different angle, showing my new design.

I claim:

The ornamental design for an ash tray, as shown.

WILLIAM N. NELSON.
